J. SKWAREK.
SCISSORS BAYONET.
APPLICATION FILED JAN. 18, 1918.

1,260,723.

Patented Mar. 26, 1918.

UNITED STATES PATENT OFFICE.

JOHN SKWAREK, OF LANSING, MICHIGAN.

SCISSORS-BAYONET.

1,260,723.

Specification of Letters Patent. Patented Mar. 26, 1918.

Application filed January 18, 1918. Serial No. 212,454.

To all whom it may concern:

Be it known that I, JOHN SKWAREK, a subject of the Emperor of Austria, residing at Lansing, in the county of Ingham and 5 State of Michigan, have invented certain new and useful Improvements in Scissors-Bayonets, of which the following is a specification.

The primary object of this invention is 10 the provision of an attachment for rifles adaptable as a bayonet and serviceable in cutting wires such as are employed to form barriers or entanglements.

A further object of the device is to 15 provide a bayonet attachment having a cutting member in the form of scissors readily operable by the soldier carrying the gun for cutting wires or the like and adapted for inoperative positioning when not in use.

20 A still further object of the device is the provision of a combined bayonet and scissors attachment for guns, the device having a cutting member adapted to be latched in its closed position when not in use and 25 resiliently maintained open when positioned for cutting articles such as wires.

In the drawing forming part of this application and in which like designating characters refer to corresponding parts 30 throughout the several views,

Figure 1 is a side elevation of the device mounted upon the end portion of a gun barrel and with the bayonet and pull cord broken away.

35 Fig. 2 is a plan view thereof, and

Fig. 3 is a similar view of a portion thereof with the cutting member closed.

My device is herein illustrated in connection with the barrel 10 of a gun or rifle and 40 includes an attaching shank 11 provided with mounting collars 12 for retaining the device upon the gun barrel by means of clamping bolts 13, a bayonet 14, diamond-shaped in cross section, being formed integral with the shank 11.

A block 15 is provided at the point of attachment between the bayonet 14, shank 11 and outer collar 12, having spaced parallel ears 16 between which a scissors blade 17 is 50 pivoted by means of a pin 18'. The said blade has a sharpened inner edge 18 for engaging the adjacent edge 19 of the bayonet 14, an elongated handle 20 being carried by the said blade 17 operable by pull cord 21 55 to be held in the hand of the soldier carrying the gun for readily contacting the

blade edge 18 with the bayonet edge 19 in severing desirable objects.

A positioning spring 22 is secured at one end, as at 23, to an offset portion 24 of the 60 shank 11, the inner end of said spring having a U-shaped bearing 25 slidably receiving the handle 20 therein. A struck-out portion 26 of the spring 22 forms an auxiliary spring bearing against the offset portion 24 65 of the shank 11 for imparting a lateral impulse to the handle 20 which handle is normally held with the scissors open by means of the spring 22.

A latch 27 is swingingly carried by the 70 inner end of the shank 11 adapted for positioning in a slot 28 at the free end of the handle 20, a cross pin 29 carried by said latch being adapted for seating within sockets 30 in the slotted portion of said handle. 75 When the handle 20 is moved adjacent the shank 11 and the spring 22 thereby compressed, the latch 27 is engaged with the pin 29 thereof seated within the sockets 30 and the auxiliary spring member 26 tending to 80 separate the shank 11 and handle 20 laterally maintains the latch in place with the scissors member in its closed position. Upon releasing the latch 27, the spring 22 forcibly moves the handle 20 away from the shank 85 11 with the blades 18 and 19 separated and the scissors member in its open position ready for use in cutting wires or other articles by pulling upon the cord 21. A serviceable attachment for guns is provided in 90 which a scissors member is combined with the bayonet detachably carried by the gun in such a manner as to add very little weight to the device. The wire cutter may be readily employed for use whenever the occasion arises. 95

What I claim as new is:—

1. A device of the class described comprising a bayonet having a mounting shank, a blade member pivoted adjacent the base 100 of the bayonet with a cutting edge adapted to coöperate with the adjacent edge of the bayonet during a cutting operation, resilient means slidably engaging said cutting member for normally maintaining the same in 105 its open arrangement, an operating pull cord for the said cutting member, a swinging latch upon said shank adapted for maintaining the cutting member in its closed position, the said resilient means having an 110 auxiliary spring portion adapted for laterally separating the said shank and cutting

member for maintaining the latch in its operative arrangement.

2. In combination with a gun barrel, a shank detachably mounted thereon, a bayonet carried by said shank in substantial alinement therewith, a block arranged at the point of connection between the said shank and bayonet, a scissors blade pivoted to the said block having a forwardly projecting cutting blade adapted for coöperation with the adjacent edge of the bayonet and further having an elongated handle projecting adjacent the said shank, a pull cord for the handle, a swinging latch at the end of the shank adapted for engaging the free end of the handle when the cutting device is closed.

3. In combination with a gun barrel, a shank detachably mounted thereon, a bayonet carried by said shank in substantial alinement therewith, a block arranged at the point of connection between the said shank and bayonet, a scissors blade pivoted to the said block having a forwardly projecting cutting blade adapted for coöperation with the adjacent edge of the bayonet and further having an elongated handle projecting adjacent the said shank, a pull cord for the handle, a swinging latch at the end

of the shank adapted for engaging the free end of the handle when the cutting device is closed, a leaf spring having one end secured to the shank adjacent said block arranged with an auxiliary spring portion contacting the said shank and with its opposite end arranged with a bearing slidably mounted upon the handle, whereby the handle is normally impelled away from the said shank with the cutting device in its open arrangement.

4. A device of the class described comprising a shank having an offset portion, a mounting block attached to the offset portion of the shank, a scissors member pivoted in said block having an elongated handle arranged adjacent the said shank, a leaf spring secured to the offset portion of the shank adjacent said block having a struck-out auxiliary spring member engaging the offset portion of the shank, a U-shaped bearing at the free end of the spring slidably maintained upon the adjacent side of the handle whereby the latter is normally maintained separated from the said shank in both side and edgewise directions.

In testimony whereof I affix my signature.

JOHN SKWAREK.
